8 Claims. (Cl. 62—140)

1

This invention relates to self-contained room air conditioners, and more particularly to console type air cooled air conditioners for installation in a room adjacent to a window.

A general object of this invention is a small, compact, simple air conditioner structure of high operating efficiency, that is well adapted to quantity production at low cost. More specific objects attained by the new structure disclosed herein are enumerated following:

1. A unit air conditioner constructed with a sheet metal chassis, and a wood cabinet of separate panels, which panels may be made in quantity production at low cost and quickly assembled separately and directly to the chassis in the final assembly operation on a quantity production assembly line.

2. A unit air conditioner constructed with a wood cabinet having a separate wood front panel easily removable for inspection of, and access to, the principal internal mechanism parts.

3. A unit air conditioner constructed with a wood cabinet comprising separate panels tightly assembled to a rectangular sheet metal chassis so that the forces and shocks of handling and shipping will be transferred through the wood panels as compression forces borne by the chassis, thus eliminating the need for protective structural strength in the shipping container therefor, and eliminating the need for shipment of a wood cabinet in a separate container.

4. A unit air conditioner constructed with a one piece welded, rectangular sheet metal chassis enclosed in a low cost wood cabinet comprising two L shaped wood panels demountably attached to the chassis sides and extending around the chassis front corners to hold in position a separately demountable wood front panel, and a wood top panel attached with hinges to the upper rear portion of the chassis.

5. In a unit air conditioner a condensing unit constructed with a three phase air cooled condenser including (1) a fin tube condenser; (2) an evaporative condenser integral with the condenser blower housing and adapted for using water vapor condensate; and (3) a parallel bare tube condenser comprising extensions of the tubes of said first fin tube condenser.

6. A console type air cooled air conditioner wherein the condenser coil occupies substantially the full internal area of a horizontal cross section of the cabinet to achieve exceptional compactness without sacrificing any part of the required condenser surface for efficiently handling the full rated capacity of the unit.

2

7. A unit air conditioner including an air cooled condensing unit having its refrigerant discharge conduit from the compressor in direct series communication with a serpentine tube metallically fused to the scroll of the condenser blower housing for utilizing the blower housing as an evaporative condenser for cooling hot refrigerant vapor and for evaporating water vapor condensate into the outgoing condenser air stream.

8. A unit air conditioner with an air cooled condensing unit mounted in a rectangular sheet metal chassis wherein the compressor unit and the condenser blower motor are supported on transverse metal rails having only their ends attached to the chassis at its internal corners, to accomplish sound isolation and exceptional quietness of operation.

9. A console type air conditioner adapted for receiving and discharging condenser air through a window duct, constructed with a condenser air inlet duct and discharge duct in its upper rear cabinet portion, a window duct adapter frame of horizontally tongue and grooved boards adapted for being selectively located in the register with said cabinet ducts, and tongue and grooved fill-in boards of different widths conterminous with said adapter frame and interchangeable in vertical assembly positions for selectively locating the duct adapter frame in register with the window duct.

From the experiences of reduction to practice, laboratory testing, and the sale and use of commercial production air conditioners in the market embodying this invention, it has been determined that an air conditioner having a one horse power compressor and a cooling capacity of approximately 11,000 B. t. u. per hour may be constructed within a cabinet having outside dimensions of 43 inches in height, 29½ inches in width, and 18 inches in depth. This is considerably smaller than other console type air cooled air conditioners currently on the market of approximately the same capacity and horse power rating. This smaller size is made possible by the structure disclosed herein, and this smaller size is an important advantage both from the standpoint of appearance with other room furnishings and for installation within limited space.

The usual cabinet structure for a console type air conditioner is a unitary structure comprising two side panels, a front panel, and a cabinet top all assembled into a cabinet structure and adapted to fit over the air conditioner mechanism assembled within a chassis. This conventional type

of air conditioner cabinet has several disadvantages that are overcome by the cabinet structure disclosed in this invention. It is expensive to assemble the individual wood panels into a separate cabinet structure in a wood working plant, or department, separate from the final assembly line for the complete air conditioner. A wood cabinet assembly is not structurally strong enough to support and carry the internal air conditioner mechanism in handling and shipment from the factory to the final user. The conventional one piece wood cabinet must be crated and shipped separately, and then finally assembled to the air conditioner chassis at the point of installation.

The wood cabinet of this invention is fabricated in panels by quantity production mill work processes and are delivered as separate panels to the air conditioner assembly line for attachment to the air conditioner chassis in the final assembly operation. The panels are assembled in close contact to the chassis so that the cabinet partakes of the structural strength of the chassis. All strains, forces, shocks, and pressures of handling, crating, shipping, and stacking in a warehouse, are transferred directly through the wood panels as compression forces against the heavy one piece steel chassis. It costs much less to produce the panels of this invention and assemble them in final assembly directly to the chassis, separately, than it does to produce a conventional one piece wood cabinet. It is not necessary to ship the cabinet separately, and therefore this invention eliminates the extra cost and work of separate crating and shipping of the wood cabinet to the point of final installation. The substantial cabinet cost reduction of this invention makes possible a retail selling price reduction that puts the console air conditioner within the price range of other major household appliances.

The principal engineering problems involved in constructing small air cooled console type air conditioners are those of heat rejection in the condensing unit, and the rejection of condensed water vapor from the evaporator. This specification will disclose in detail a new three phase air cooled condenser for the condensing unit of a small air conditioner that will efficiently reject the heat absorbed by the evaporator and operation of the compressor and motor, and that will effectively use all the latent cooling capacity of the condensate by evaporating it in the condenser blower scroll constructed as an evaporative condenser. This new condenser structure makes it possible to build more condensing capacity into a smaller space within an air conditioner chassis. This condenser structure is largely responsible for the exceptionally small and compact size in which air conditioners may be built when embodying this invention.

These and other objects and advantages of this invention will more fully appear from the following description made in connection with the accompanying drawings, wherein like reference characters refer to similar parts throughout the several views, and in which:

Fig. 1 is a front perspective view of an air conditioner of this invention having a wood console type cabinet.

Fig. 2 is a rear perspective view of Fig. 1 showing the cooling air inlet and outlet openings.

Fig. 3 is a front elevational view of Fig. 1 with the front cabinet panel removed to show the internal mechanism.

Fig. 4 is a vertical sectional view of Fig. 3 taken at the section lines 4—4.

Fig. 5 is a projected view of the blower housing 20 of Fig. 4 showing its left hand side with a serpentine refrigerant conduit metallically bonded to the outside of its scroll.

Fig. 6 is a projected view of the blower housing 20 of Fig. 4 showing its right hand side with a continuation of the serpentine refrigerant conduit of Fig. 5 metallically bonded to the blower scroll.

Fig. 7 is a horizontal cross sectional view of Fig. 4 at section lines 7—7, looking vertically downward into the air conditioner.

Fig. 8 is a rear elevational view of the removable front panel of the air conditioner cabinet shown in Fig. 1.

Fig. 9 is an inside elevational view of the left hand cabinet side panel shown in Fig. 1.

Fig. 10 is a perspective view of a chassis for an air conditioner of this invention.

The chassis of Fig. 10 is constructed with a right hand sheet metal side panel 12 and left hand side panel 13 aligned in parallel relation and joined by welding to interposed L-shaped partition 14 and bottom pan 15. The chassis side panels have front flanges 16, and rear flanges 17, and are constructed with rectangular openings 18 for the inlet of recirculated cooled air through the air conditioner. The left hand side panel 13 has a circular opening 19 in its lower portion for access to the inside of blower housing 20 shown assembled thereto in Figs. 3 and 4. In the lower portion of right hand side panel 12 is a circular opening 21 used for access through the panel during assembly, inspection, and service.

The chassis side panels 12 and 13 have each two bolt holes 22 symmetrically spaced for bolts 23 used to secure the cabinet side panels 24 to their respective sides of the chassis. The front flanges 16 of the two chassis side panels 12 and 13 have each two bolt holes 25 symmetrically spaced for bolts 26 to secure cabinet side panels 24 to their respective sides of the chassis. Thus each side panel of the cabinet is secured to its respective side of the chassis with four bolts, and by means of these bolts may be readily assembled to, or disassembled from, the chassis.

The chassis bottom pan 15 has sides 27 formed vertically upward and welded water tight at the corners. The flanged sides 27 are spot-welded to chassis side panels 12 and 13 respectively, and to front flanges 16 and rear flanges 17 of the chassis side panels. Thus pan 15 serves as a transverse structural member for the chassis, and in addition it is used to catch condensate that might accidentally drop from the air conditioning mechanism. Any condensate that falls into pan 15 will be distributed over a considerable surface area and subjected to a flow of heated air, as will be hereinafter explained, to re-evaporate the condensate into an outgoing stream of condenser cooling air.

The L-shaped partition 14 has at each end vertical flanges 28 formed on its vertical portion, and has at each end horizontal flanges 29 formed on its horizontal portion, as shown in Fig. 4. These flanges 28 and 29 are spot-welded respectively to chassis side panels 12 and 13 so that the partition 14 becomes a transverse structural member of the chassis. In addition to being a structural member of the chassis partition 14 in its upper vertical portion, it provides one side of each of the two condenser cooling air ducts, and its lower horizontal portion provides a sup-

porting base for the evaporator assembly of the air conditioner, as will be hereinafter more fully described, and in addition it supports the condenser 55 suspended beneath it.

At the upper portion of the chassis is a horizontal sheet metal member 30 spot-welded to the top of partition 14. At each end of member 30 are flanges 31 spot-welded respectively to chassis side panels 12 and 13 so that member 30 becomes also a transverse structural member of the chassis. Member 30, in addition to being a chassis structural member, is a top for both the condenser cooling air inlet and outlet ducts.

The two cabinet side panels 24 have rectangular openings 32 in register with the chassis side panel openings 18 through which cooled air is drawn into the air conditioner for recirculation. An air inlet louver 33 is assembled within the openings 18 in each chassis side panel 12 and 13. These louvers may be assembled, as an alternate, within the opening 32 of each cabinet side panel 24. Whether louver 33 is assembled to the chassis side panels as shown, or to the cabinet side panels 24, is a manufacturing choice giving about the same end results since cabinet side panel openings 32 and chassis side panel openings 18 are in contiguous register.

Cabinet side panels 24 are constructed in an L-shaped section so that each side panel has a flange 34 extending around its respective front corner of the cabinet chassis covering at least a portion of the front flanges 16 of the chassis side panels 12 and 13. In assembly bolts 26 hold flanges 34 tightly in flat contact with chassis flanges 16 so that the inside corners of the side panels 24 fit around the front corners of chassis panels 12 and 13 in full contact. Bolts 23 secure the rear portions of the cabinet side panels 24 in flat contact with the respective chassis side panels 12 and 13. Thus any compressive forces upon the outside of the cabinet side panels will be referred directly to the respective chassis side panels underneath, and the structural strength of the sheet metal chassis panels will support the wood side panels 24 of the surrounding cabinet. Fiber board insulation 35 is glued to the inside surface of the side panels 24 for the purpose of restricting the transmission of heat and sound through the panels.

In the edges of cabinet side panel flanges 34 are grooves 36 arranged to receive the side edges of cabinet front panel 37. The cabinet is constructed by assembling its separate portions to the air conditioner chassis. First the two cabinet side panels 24 are assembled to the chassis as explained above. The front panel 37 is constructed so that it is assembled to the front of the cabinet by sliding it vertically downward with its side edges fitting the grooves 36 in the cabinet side panel flanges 34. The front panel 37 is retained by its bottom side portions resting upon flanges 38 at the front bottom of the chassis side panels 12 and 13. Reinforcing wood strips 39 are provided inside the front panel 37 which may be made of plywood, and fiber board insulation 40 is provided for restricting the transmission of heat and sound through the panel 37.

A circular opening 41 is provided in front cabinet panel 37, shown in Fig. 8, and a louver 42 is assembled behind this opening as shown in Fig. 1. This opening and louver is for the outlet of cooled air from the air conditioner.

The back cover of the air conditioner cabinet is constructed of several parts which will be described and explained in detail. At the lower

rear portion of the cabinet is a removable sheet metal panel 44 insulated with fiber board 93 and assembled to the rear chassis side panel flanges 17 with sheet metal screws. Just above removable panel 44 and extending under its upper portion, is a sheet metal transverse chassis structural member 45 spot-welded at each end to the inside of flanges 17 of the chassis side channels. This transverse structural member adds strength to the chassis, it provides support for the top of removable panel 44 to which panel 44 is attached with sheet metal screws, and it provides a support for an interchangeable series of wooden rear panel parts which will be described following.

Above transverse chassis member 45 and resting upon it is tongue and grooved board 46 having its groove downward and its tongue upward. Above board 46 is a second tongue and grooved board 47 assembled in tongue and groove register with board 46. Board 47 is substantially narrower than board 46. Above board 47 is a rectangular, wooden, tongue and grooved duct collar frame 49 assembled in tongue and groove register with board 47. Above duct collar frame 49, and assembled in tongue and grooved register with it, is tongue and grooved board 48 having its upward positioned tongue top in a plane with the tops of the chassis side panels 12 and 13.

The cabinet top panel 52 is hinged to transverse tongue and grooved board 48 with hinges 53. This top panel may be made of plywood.

Within the duct collar frame 49 is assembled rectangular sheet metal air outlet duct collar 50, and rectangular sheet metal air outlet duct collar 51. These collars are arranged for the attachment of ducts extending through a window for the intake and discharge of condenser cooling air. Such a duct is not shown herein since it may be constructed in the usual way, and is not a part of this invention. The tongue and grooved boards 46, 47 and 48, and the duct collar frame 49 are secured to the inside of the flanges 17 of the chassis side panels 12 and 13, by means of bolts at their ends. These four parts are interchangeable in their vertical assembly relationship. Thus the duct collar frame 49 may be selectively arranged in different vertical locations within the back panel assembly of the cabinet. Boards 46, 47 and 48 are made of different widths selected to give the greatest variety of locations for selectively positioning the duct collars. If the exact location for the duct collars cannot be obtained as desired from an assembly of the three tongue and grooved boards in any of their possible combinations, then one of the tongue and grooved boards may be sawed longitudinally into two widths which when separated and relocated will provide the exact vertical spacing of the duct collars desired.

A rectangular sheet metal partition 43, shown in Fig. 7, between the tongue and grooved wooden members of the cabinet back panel, and the vertical portion of the L shaped partition 14, separates the condenser air inlet duct from the condenser air outlet duct. This partition 43 is in alignment and contact with the separating flange 54 between the duct collars 50 and 51, and this partition contact will be had in all vertical positions of the duct collars within the limits of their selective assembly.

A fin tube condenser 55 is constructed with a right hand header plate 56 and a left hand header plate 57. Both of these header plates are rectangular and flanged with holes in the flanges for assembly bolts. Both the condenser coil and its

header plates extend transversely across the full internal width of the air conditioner so that the front and rear panels of the air conditioner serve as duct portions to confine and direct the flow of condenser cooling air through the condenser as will hereinafter be described in detail. The condenser header plate 57 is constructed in alignment with duct partition 43 above to which it is bolted. Header plate 57 is in effect a duct partition dividing and separating the incoming and outgoing condenser cooling air.

The length of the condenser coil 55 including its extended end bends 58 is substantially equal to the inside width of the air conditioner chassis so that the chassis side panel 12 serves as a side to the condenser air inlet duct, and chassis side panel 13 serves as a side to the condenser air outlet duct.

The condenser is assembled within the air conditioner by bolting its flanged header plates to the lower portion of the L-shaped partition 14 as shown in Figs. 3 and 4. The condenser air blower housing 20 has its outlet constructed to extend laterally across the full depth of the inside of the cabinet. Its left side has an opening not shown which is assembled in register with circular opening 19 in chassis side panel 13, and the blower housing is secured to the side panel 13 by means of bolts. The right side of blower housing 20 is constructed in alignment with header plate 57 of the condenser coil and is bolted thereto as shown in Figs. 3 and 4. Extended end bends 58 of the tubes in the fin tube condenser 55 extend laterally across substantially the full width of the discharge air outlet of the blower housing 20.

Blower housing 20 comprises blower scroll 59 to which a serpentine tubular conduit 60 is metallically fused as shown in Figs. 4, 5 and 6. The serpentine conduit 60 may be made of steel and spot-welded at intervals to the blower scroll 59, and then metallically fused to the scroll by hot dip galvanizing. As an alternate serpentine conduit 60 may be a copper tube secured at intervals to the scroll 59 with U-shaped clips (not shown) spot-welded to the scroll, and then the serpentine tube being metallically fused to the scroll by hot dip galvanizing. The serpentine conduit 60 has its inlet at its end 61, and its outlet at its other end 62.

Within blower housing 20 is centrifugal blower wheel 63 driven by motor 64. Adjacent to motor 64 is an hermetic type refrigeration compressor 65. The blower motor and the compressor of this invention have a novel and effective mounting by which their sound of operation is isolated effectively for accomplishing exceptional quietness of operation. This mounting will be described in detail following.

At the lower front portion of chassis side panels 12 and 13, inside their front flanges 16 are arc welded short steel angles 66, one to each side panel. The angles 66 are fit into their respective corners of the chassis side panels and are secured by arc welding at both sides of the corners to support front mounting rail 67 and to secure it with bolts at each of its ends. At the lower rear portion of the chassis side panels 12 and 13, inside their rear flanges 17 are arc welded short steel angles 68, one to each side panel. The angles 68 are fit into their respective corners as are angles 66, and are secured by arc welding at both sides of the corners to support rear mounting rail 69 and to secure it with bolts at each of its ends.

A channel member 70 is supported at one end by front mounting rail 67 to which it is bolted,

and is supported at its other end by rear mounting rail 69 to which that end is bolted. Blower motor 64 is mounted upon and bolted to channel member 70. Two compressor mounting angles 71 are supported at their front ends by front mounting rail 67 to which they are bolted, and are supported at their other ends by rear mounting rail 69 to which those ends are bolted. Compressor 65 is supported upon angles 71 by means of conventional compressor mounting spring assemblies 72. Thus the full weight of the blower motor assembly and the compressor 65 is transferred to and supported by the four inside corners of the chassis side panels 12 and 13. These corner mounting positions are the most rigid mounting positions within the chassis, and are the least susceptible to the influence and transmission of sound vibrations from the blower motor and the compressor operation. Exceptional quietness of operation is obtained by this construction for mounting the blower motor and compressor.

An evaporator assembly for the air conditioner is constructed as a unitary sub-assembly and then assembled into the chassis. The evaporator assembly comprises an evaporator pan 73 welded water tight at its corners for holding condensate, two fin tube evaporators 74 arranged in a V position and secured to the evaporator pan, an evaporator fan 75, an evaporator fan motor 76, a fan motor mounting bracket 77 secured to the evaporator pan 73 for supporting the fan and motor assembly, a refrigerant expansion valve 78, and a refrigerant accumulator 79. L-shaped partition 14 defines the bottom and rear wall of the evaporator chamber within the air conditioner chassis. Fiber board insulation 80, imposed upon the lower portion of partition 14 insulates the bottom of the evaporator chamber, and fiber board insulation 81 against the vertical part of partition 14 insulates the rear wall of the evaporator chamber. Fiber board insulation 82 assembled over chassis member 38 insulates the top of the condenser cooling air duct. A top panel 91 is provided for the evaporator chamber.

In the refrigerant circuit expansion valve 78 meters liquid refrigerant through conduit 83 to the two evaporators 74 which are interconnected to function as one evaporator. Conduit 84 from the evaporators 74 leads refrigerant vapor and surplus liquid refrigerant to the accumulator 79 which is arranged as a trap to retain the surplus liquid refrigerant of the system. The compressor 65 draws refrigerant vapor from accumulator 79 through conduit 85. This completes the low pressure side of the refrigerant circuit.

The compressor 65 compresses refrigerant to a condensing pressure and discharges it through conduit 86 into serpentine tube 60 at its inlet 61. The outlet 62 of the serpentine tube 60 is in communication with the inlet of fin tube condenser 55 through conduit 87. Condenser 55 is constructed with a single circuit with the refrigerant entering the bottom of its three rows proceeding upward in counterflow relation to the condenser cooling air which flows downward through the fin tube section of the condenser 55 as shown in Fig. 3. In passing through the condenser 55 the refrigerant becomes liquefied and leaves the condenser through its outlet 88 which is in communication with expansion valve 78 through conduit 89 to complete the refrigerant circuit.

A conduit 90 provides communication between the evaporator condensate pan 73 and the inside of the blower housing 20. Conduit 90 is arranged to deliver condensate by gravity to the inside of

the blower housing at a point where the air flow through the blower wheel will disperse the condensate against the inside of the blower scroll to wet a substantial portion of its surface. The blower housing 20 becomes an evaporative condenser removing heat from the refrigerant in serpentine tube 68 by evaporation of condensate within the blower scroll which is in heat transfer relation with tube 60 by reason of its being metallically fused to serpentine tube 60.

An electric line conductor cord 92 enters the cabinet through chassis member 45 shown in Fig. 2 to connect with conventional air conditioner operating circuits not shown.

In operation the evaporator fan 75 draws room air to be conditioned through the two louvers 33 in the sides of the air conditioner cabinet, through the two evaporator coils 74, and then discharges it from the cabinet through cool air discharge louver 42. When the air passes through the evaporator coils 74, heat and water vapor is removed from the air. The heat is absorbed by the refrigerant within the evaporators as it changes from a liquid to a vapor state and is carried by the refrigerant vapor into the compressor 65 where the vapor is compressed to a pressure that will cause it to give up its heat in the condenser of this invention which will be described in detail following.

The air cooled condenser of this invention is a three phase condenser. Phase one is the fin tube section of the condenser 55; phase two is the blower housing 20 which acts as an evaporative condenser as explained above; and, phase three is the condensing surface of the extended end bends 58 of condenser 55. Condenser cooling air enters the air conditioner through duct collar 50 which may be connected by a duct to outdoors air. The cooling air inlet duct is defined on four sides by the cabinet back panel assembly, a portion of chassis side panel 12, the vertical portion of partition 14, and the duct partition 43. At the top this duct is closed by chassis member 30, and at its bottom this cooling air inlet duct is open and in direct communication with the fin tube portion of condenser 55. Condenser header plates 56 and 57 and the cabinet front panel 37 confine the incoming condenser air to flowing through the fin tube section of condenser 55, from which it passes downward flowing over the compressor 65, over the blower motor 64 and into the blower housing 20.

The condenser air discharge duct from the blower housing 20 is defined on its four sides by chassis side plate 13, the cabinet back panel assembly, a portion of partition 14, and duct partition 43 together with condenser header plate 57 as one side. The top of the discharge duct is a portion of chassis member 30, and the outlet of the duct is through duct collar 51 in the cabinet back panel assembly.

Centrifugal blower wheel 63 draws condenser cooling air into the air conditioner through the condenser air inlet duct above described, thence through the fin tube portion of the condenser 55, over and around the compressor 65 and the blower motor 64 over bottom pan 15 and into the blower housing 20. Then blower wheel 63 discharges the cooling air into the blower housing 20 where the air evaporates condensate delivered through conduit 90 and absorbs heat from the refrigerant in serpentine tube 60. The cooling air then passes from the blower housing 20 at high velocity over the extended end bends 58 of the condenser 55 and into the condenser air outlet 75

duct described above. The duct collar 51 is arranged for the connection of a discharge duct to the outdoors.

The evaporative condensing in serpentine tube 60 of the blower housing 20 and the condensing within the fin tube section of the condenser 55 are arranged in counterflow heat exchange relationship within the refrigerant circuit and the condenser cooling air circuit. The hot refrigerant vapor from the compressor flows first through the evaporative condenser which is embodied in blower 20, and second through the condenser 55. The condenser cooling air flows first through the fin tube section of condenser 55 and second through the evaporative condenser embodied in blower 20. The combination of these two condensers in counterflow heat exchange relation provides very efficient condensing and low head pressures in the air conditioner of this invention.

When the cooling air passes through the fin tube section of condenser 55 it is heated several degrees by the absorption of heat from the condenser 55. When this air then passes through the blower housing 20 where it evaporates condensate, the evaporation of the condensate absorbs heat from the air and cools it in the evaporation process. The condenser air that is discharged by the blower over the condenser end bends 58 is therefore cooler than it is when it leaves the fin tube section of the condenser 55. This intercooling of the condenser air between the fin tube section and the extended end bends 58 adds new condenser efficiency to air conditioner embodying this invention.

The structure disclosed in this specification is new to the art and it accomplishes a number of advantages over the console type air conditioners now known to the art. It accomplishes the nine (9) valuable objectives enumerated in the first part of this specification. This invention has produced a small, compact, simple air conditioner structure of high operating efficiency that is well adapted to quantity production at low cost.

It is understood that this invention is not to be restricted to the exact types of parts and the particular arrangement shown in the drawings since these may be modified under the teachings of this specification and will then come within the scope of the appended claims without departing from the scope and spirit of this invention.

Having thus described and explained my invention, I claim:

1. A console air conditioner comprising a chassis, a condensing unit and an air cooling evaporator unit within said chassis, an L section side panel assembled to each side of said chassis symmetrically with its foot section covering a front corner portion of the chassis and being adapted to retain a side of a front panel, a front panel removably retained at the front of said chassis by said foot sections of said side panels, and a top panel secured to the top of said chassis.

2. A console air conditioner comprising a chassis, a cabinet enclosing said chassis, a condensing unit and an air cooling evaporator unit within said chassis, said cabinet including an L section side panel assembled to each side of said chassis symmetrically with its foot section covering a front corner portion of the chassis and being adapted to retain a side of a cabinet front panel, said side panels being conterminous with and firmly secured to the outside front corner portions and sides of said chassis, a front panel removably retained at the front of said chassis by

11.

said foot sections of said side panels, and a top panel secured to the top rear portion of said chassis.

3. An air cooled air conditioner comprising a chassis, a cabinet enclosing said chassis, said chassis comprising two vertical channel side members joined with a bottom panel and an L-shaped partition as transverse structural members, and a duct partition adjoining said L-shaped partition, said L-shaped partition arranged in conjunction with said chassis, cabinet, and duct partition to delineate an evaporator chamber, a condensing unit chamber and two cooling air ducts, an air cooling evaporator unit in said evaporator chamber, and an air cooled condensing unit in said condensing unit chamber.

4. An air cooled air conditioner comprising a cabinet constructed with a rear panel assembly, an air cooling evaporator unit and an air cooled condensing unit within said cabinet, two vertical cooling air ducts at the upper rear portion of said chassis defined in part by said rear panel assembly and arranged in communication with said condensing unit, said rear panel assembly comprising a horizontally tongue and grooved wood frame having two openings in register with said two air ducts, and a plurality of horizontally tongue and grooved boards of different widths adapted for interchangeable assembly with said wood frame for selectively positioning said wood frame vertically in said rear cabinet panel.

5. An air cooled air conditioner comprising a cabinet constructed with a rear panel assembly, an L-shaped partition within said cabinet, an air duct partition adjoining said L-shaped partition, said L-shaped partition arranged in conjunction with said cabinet and duct partition to delineate an evaporator chamber, a condensing unit chamber, and two cooling air ducts, an air cooling evaporator unit in said evaporator chamber, and an air cooled condensing unit in said condensing unit chamber in communication with said two cooling air ducts, said rear panel assembly comprising a horizontally tongue and grooved wood frame having two openings in communicating register with said two air ducts, and a plurality of horizontally tongue and grooved boards of different widths adapted for interchangeable assembly with said wood frame adapted for selectively positioning said wood frame vertically in said rear cabinet panel assembly.

6. An air cooled air conditioner comprising an enclosing cabinet, an air inlet opening and an air outlet opening for condenser cooling air in said cabinet, an air cooling evaporator unit within said cabinet, a condensing unit within said cabinet in communication with said air inlet opening comprising a fin tube condenser, a compressor, and a blower arranged to draw cooling air in sequence through said cabinet air inlet opening, through said fin tube condenser, a portion over said compressor, and finally all of the cooling air into the inlet of said blower, a duct establishing communication between the discharge outlet of said blower and the said cabinet outlet opening, and extended end bends of the

12.

tubes at one end of said fin tube condenser extending into said duct and substantially across its width.

7. An air cooled air conditioner comprising an enclosing cabinet, an air inlet opening and an air outlet opening for condenser cooling air in said cabinet, an air cooling evaporator unit within said cabinet, a condensing unit within said cabinet in communication with said air inlet opening comprising a fin tube condenser, a compressor, and a blower arranged to draw cooling air in sequence through said cabinet air inlet opening, through said fin tube condenser, a portion over said compressor, and finally all of the cooling air into the inlet of said blower, a duct establishing communication between the discharge outlet of said blower and the said cabinet outlet opening, and extended end bends of the tubes at one end of said fin tube condenser extending into said duct and substantially across its width, said fin tube condenser being disposed horizontally within said cabinet and constructed with a face area substantially equal to the internal horizontal cross sectional area of said cabinet so that the walls of said cabinet serve to retain and direct the flow of cooling air through said fin tube condenser.

8. An air cooled air conditioner comprising an enclosing cabinet, a condenser cooling air inlet opening and outlet opening in said cabinet, an air cooling evaporator unit in said cabinet, an air cooled condensing unit within said cabinet in communication with said air inlet opening, said condensing unit comprising a fin tube condenser, a compressor, and a centrifugal blower arranged to draw condenser cooling air in sequence through said cabinet air inlet opening, through said fin tube condenser, a part over said compressor, and finally all of the cooling air into the inlet opening of said blower, a serpentine refrigerant conduit metallically fused to the scroll of said blower and arranged to establish fluid communication between the discharge outlet of said compressor and the refrigerant inlet tube of said fin tube condenser, conduit means for delivering condensed water vapor from said evaporator unit to the inside of said blower, a duct establishing communication between the discharge outlet of said blower and said cabinet outlet opening, and extended end bends of the tubes at one end of said fin tube condenser extending into said duct and substantially across its width.

ALLEN TRASK.
